UNITED STATES PATENT OFFICE.

CHARLES S. BURTON, OF OAK PARK, ILLINOIS, ASSIGNOR, BY MESNE ASSIGNMENTS, TO THE CLEVELAND GRAPHITE BRONZE COMPANY, OF CLEVELAND, OHIO, A CORPORATION OF OHIO.

REBOUND CHECK FOR VEHICLES.

Application filed February 7, 1923, Serial No. 617,424. Renewed December 22, 1924.

The purpose of this invention is to provide an improved construction in a rebound check for spring vehicles of the type comprising a spring-retracted drum mounted on one of the vehicle members and connected with the other for tensioning the drum spring against the vehicle spring in the rebound of the vehicle, and having also means for frictional resistance to the rebound. It consists of the elements and features of construction shown and described as indicated in the claims.

In the drawings:—

Figure 1 is a side elevation of a construction embodying this invention shown mounted in connection with the chassis and axle of a vehicle to be served thereby.

Figure 2 is an axial section of the main element of the device.

Figure 3 is a section at the line 3—3 on Figure 2.

Figure 4 is a section at the line 4—4 on Figure 2.

Figure 5 is a detail section at the line 5—5 on Figure 2.

Figure 6 is a view similar to Figure 3 showing a modified construction.

Figure 7 is a detail of a facing and hinging plate for the brake shoe shown in Figure 6.

The shock absorber shown in the drawings is of a type characterized by two features, (a) a drum on which a check strap which connects the vehicle body and axle is wound for taking up slack yielded in the descent of the vehicle, by the reaction of a spring connected for rotating the drum, the spring being tensioned in the rebound of the vehicle by the unwinding of the check strap, the rebound being checked by the resistance due to the tension of the spring; (b) means for frictional resistance to the rotation of the drum, which resistance is added to the spring resistance in the rebound movement of the vehicle body.

The present invention is characterized also by means and features of construction for producing the frictional resistance to the drum for rotating without application of lateral pressure, and, at least in the preferred form, also without pressure directed toward the axle,—i. e. so as to press the drum against its journal bearing or axle, all the brake pressure applied being substantially balanced as to its tendency to thrust the drum against the axle. Other characteristic features are the specific means employed for brake pressure

and means of adjusting said pressure at will; 55 a mounting brake or adapter for mounting the device on the vehicle adapted for a variety of connections suitable for different vehicles; and, in the preferred form, means for applying the brake pressure adapted to relax the 60 braking effect in the direction of rotation of the drum in which it takes up the slack of the connector, and increasing said braking action in the rotation of the drum in the opposite direction,—i. e. when it is rotated by unwinding the strap for tensioning the spring.

In the drawings, A represents a portion of the chassis of the vehicle to be served; B the axle toward and from which the chassis and vehicle body moves in the descent and rebound due to irregularities of the roadway. 70 C, is the casing of the rebound check device which is shown mounted on the chassis. 4 is the check strap connected to said device and to the axle thereby connecting the axle and vehicle body. 5 is a stud axle or journal bearing which in service of the device on the car is fixedly mounted with respect to one of the connected elements, viz., vehicle body or chassis and axle, the mounting in the present 75 instance being upon the chassis as stated; the means of mounting being hereinafter more particularly described. 6 is a drum mounted for rotation upon the stud axle, 5. This drum comprises a transaxial diaphragm, 85 6^a, and cup cavities, 6^b and 6^c, at opposite sides of the diaphragm. The cavity, 6^b, accommodates the rebound-check-spring, 7, which has its inner coil engaged with a paraxial slot, 5^a, in the stud axle and its outer coil 90 connected by a link, 5^b, with the peripheral flange, 6^d, of the drum. The cavity, 6^c, is closed by a cap plate 6^e, whose periphery interlocks non-rotatably with the flange, 6^d, as shown. In the cup cavity, 6^c, there are 95 mounted segmental brake shoes, 8, 8. In the form shown in Figure 3 both brake shoes are carried by an inner facing strip, 10, of spring metal which is shaped to form an eye, 10^a, for pivoting both brake shoes to the same pivot 100 stud, 12, closely adjacent to the flange, 6^d, of the drum, said stud being carried on the inner side of a plate, 11, non-rotatably mounted on the stud axle. Preferably the spring carrier and facing strip, 10, normally,—that is, at 105 neutral position,—holds the segment brake shoes neutrally in contact or even slightly out of contact with the inner face of the flange,

6^e. For pressing the brake shoes into contact with the flange for producing the desired frictional resistance to the rotation of the drum, there is provided mounted radially on 5 the outer side of the plate, 11, radially with respect to the stud axle, and rotatable at its said mounting, a threaded stem, 15, which extends alongside the drum and out through the periphery of the casing hereinafter described. On this threaded stem there is mounted a travelling nut, 16, having a wing, 16^a, projecting laterally through a slot, 11^a, in the plate, 11, into the cup cavity, 6^c, and within said cavity carrying rigidly attached there- 10 to and thereby rigidly attached to the nut, two stiff flat-metal springs, 17, 17, whose free ends bear against the inner metal faced edges of the brake shoes, 8, 8. The brake shoes each being a segment less than 180° have their said 15 inner metal faced edges preferably converging toward their free ends and the said flat metal springs, 17, at what may be regarded as medial or usual position of the nut, 16, on the threaded stem, 15, have their free ends bearing with moderate pressure outward with respect to the axis of the drum against said inner edges of the brake shoes holding said brake shoes pressed yieldingly against the flange, 6^d. The outer end of the said threaded 20 stem, 15, is squared for receiving a key by which it may be rotated to cause the nut to travel in or out along the stem whereby when the nut is moved outward, the free ends of the two springs are wedged together as they are 25 forced along the converging edges of the two brake shoes and thereby the tension of the springs is increased; and the pressure by which they hold the brake shoes against the inner face of the flange, 6^d, is increased not 30 only by the increased tension of the springs but also by the circumstance that this increased tension operates with the advantage of increased leverage as the springs are moved along the brake shoes away from the fulcrums 35 of the latter; and, on the other hand, when the nut is caused to travel inward along the stem the pressure against the brake shoes is diminished and the friction of the shoes against the drum is correspondingly diminished. 40

The structure above described is enclosed in a casing comprising a cup-shaped member, 20, for which the plate, 11, constitutes a cap or closure, said plate being suitably dimensioned for that purpose and having a peripheral flange, 11^b, adapted to embrace the edge of the flange or circumferential wall, 20^a, of the casing member, 20, and to interlock therewith by outstruck hollow bosses, 45 11^c, in said flange, 11^b, engaging bosses, 20^c, registeringly positioned on the flange, 20^a, of the casing member. The stud axle, 5, is reduced and threaded at one end forming a shoulder, 5^e, and onto said reduced threaded end there is applied a nut, 23, which is

screwed up tight against said shoulder, the nut being of sufficient diameter to overlap the margin of the central aperture of the casing member, 20, for retaining the same on the stud. At the opposite end outside the 70 squared portion, 5^d, provided for non-rotatably engaging the plate, 11, the stud axle, 5, is slightly reduced in diameter to form a shoulder, and is threaded to receive a nut, 24, which similarly to the nut, 23, overlaps the 75 margin of the central aperture of the cap member, 11; and thereby the casing members, 20 and 11, are held interlocked between the two nuts, 23 and 24.

The check strap, 4, is attached at one end 80 positively to the drum for winding upon the outer side thereof and in assembling is wrapped once or more about the drum and extends out through a peripheral opening, 20^e, in the casing member, 20.

For mounting the device upon the vehicle there is provided a mounting bracket or adapter, 25, which comprises a hub, 25^a, having at one end a flange, 25^b, provided with a plurality of bosses, 25^c, (as shown, four) projecting from the face of the flange at a distance from the center of the hub and flange sufficient to admit within the inner ends of said bosses, the nut, 23, and recessed as seen at 25^d, to accommodate said nut. This hub is axially bored and threaded for screwing into it the reduced and threaded end, 5^e, of the stud axle, 5; and the cup member, 20, of the casing has its bottom wall or web provided with four outwardly struck bosses, 20^e, 10 for engagement between the bosses, 25^c, for holding the casing non-rotatable with respect to the bracket. The opposite end of the bracket hub is slightly reduced and threaded as seen at 25^e. Preferably, for attaching this 15 bracket so as to afford means of mounting the device in different situations as may be required by the construction of different vehicles, there is extended from it at one side radially an angle arm, 25^f, having its face 11 toward the casing offset back therefrom to accommodate the head of a bolt indicated at 30 for securing the bracket and thereby the entire device to a frame bar of the body of the vehicle. It is contemplated that the 16 bracket may be mounted in any one of at least three ways on the customary channel side bar of the chassis, to wit (1) by inserting the threaded end, 25^e, of the bracket through a hole which may be bored in the vertical web of the channel bar and securing it by a nut; (2) by applying the angle of the angle arm, 25^f, embracing the lower angle of the channel bar and securing it through either or both of the arms of the angle by bolts projecting respectively into the vertical web and the lower horizontal flange of the channel bar, or (3) by stepping the horizontal limb of the angle arm, 25^f, upon the upper horizontal flange of the channel side bar and bolting it 13

thereto. It will be seen also that the adapter bracket may be applied to the casing, 20, in a position 90° turned either way from that at which it is shown in the drawings, whereby 5 the adapter bracket will serve for securing it to a vertical member of the vehicle frame or body if such member is conveniently present.

It will be seen upon consideration that the 10 brake shoes both pivoted at the same point on the web of the drum and being for braking pressed more or less against the flange of the drum will exert different amounts of 15 braking effect upon the drum, for the reason that as the drum rotates in one direction, the shoe along whose friction face the flange moves from the free end toward the pivoted end will be hugged by the friction against the flange and have greater frictional effect 20 than that of the other shoe along which the flange of the drum travels from the pivoted end toward the free end; so that one shoe will be more effective for friction in the rotation of the drum in one direction and the other shoe will 25 be more effective for friction in the rotation of the drum in the opposite direction. But the total friction upon the drum will be the same in both directions of its rotation. In the 30 operation of a rebound check of this character frictional resistance to the rotation of the drum is no advantage in the descending movement of the vehicle and is desirable only in the rebound. It is undesirable in the descent for the reason that it is most important 35 that the spring which rotates the drum for taking up the slack of the check strap shall be able to act quickly enough to take up the slack and in fact to prevent any actual slack, in case of a most sudden and rapid descent of the vehicle, since otherwise the vehicle will 40 receive a shock and there will be caused an unpleasant slapping action of the strap on the drum when the action of the spring taking up the slack overtakes the downward movement 45 of the vehicle. When the means of applying to the drum the friction which is desirable to supplement the action of the spring for checking the rebound is such as to impose friction during the descent, it is necessary to 50 tension the spring so much the tighter in order to insure its quickness of action for taking up the slack. To avoid this objectionable friction in the descent of the vehicle the form 55 shown in Figure 6 is regarded as preferable. In this figure the two brake shoes, 80, 81, instead of being pivoted at the same side of the cup cavity of the drum in which they are contained, are pivoted to the plate, 11, at 60 diametrically opposite points, so that in rotation of the drum in one direction its flange travels over both shoes from the free end to the pivoted end, and in the other direction travels over both shoes from the pivoted end 65 toward the free end. The shoes are pivoted with respect to the direction of the winding

of the strap on the drum so that the unwinding movement in which the spring is tensioned, the flange of the drum travels along the shoes as first mentioned,—that is, from the free end toward the pivoted end thereby 70 causing both shoes to hug the flange and afford the maximum friction; and in the opposite movement in which the spring is reacting for taking up the slack while the vehicle descends, the flange travels over both shoes 75 from the pivoted end to the free end and therefore with minimum friction on both shoes.

In this form, in order that the frictional action of both shoes shall be increased or diminished alike by the adjustment of the brake spring-carrying nut along the threaded stem, 15, since the leverage on either shoe is diminished by the adjustment which increases the leverage on the other shoe, the shoe, 81, 20 along which the spring moves toward the fulcrum when adjustment is made for increasing the pressure of the shoes is shaped at its inner edge on which the spring bears and slides in 25 said adjustment, so as to flex the spring for 30 increased tension in that adjustment, the wedging slope of said edge being calculated to more than offset the reduction of pressure due to the reduction of leverage and substantially to equalize the pressure gain or loss 35 of the two shoes. 40

I claim:—

1. A rebound check for spring vehicles comprising in combination with a drum mounted rotatably on one of the two vehicle members between which the vehicle springs react, a stud axle on which the drum is rotatably mounted, said drum having a transaxial diaphragm and cavities at opposite sides of said diaphragm, the spring for yieldingly resisting the rotation of the drum and retracting it being mounted in one of said cavities, the brake shoe being mounted in the other cavity for frictioning against the peripheral wall of said cavity, a bearing member 100 for the drum on the stud spaced axially from the diaphragm on the side of the spring cavity, spanning the lateral opening thereof and non-rotatably engaged with the drum flange 105 at that side. 110

2. A rebound check for spring vehicles comprising in combination with a drum mounted rotatably on one of the two vehicle members between which the vehicle springs react, a stud axle on which the drum is rotatably mounted, the drum having a cavity at one side, the brake shoe being mounted in said cavity, a transaxial member non-rotatably engaged with the stud axle, on which member the brake shoe is mounted; a spring carried by the stud axle reacting on the brake shoe for pressing it outwardly with respect to the axle for its friction bearing against the inner peripheral wall of said cavity; a threaded stem mounted rotatably radially with re- 120 125 130

- 5 spect to the stud axle and laterally with respect to the zone of the brake shoe; a nut on said stem having a projection extending laterally of said stem into said cavity of the
5 drum in the zone of the brake shoe, the brake shoe spring being carried by said nut and means for rotating the threaded stem to shift the nut along the latter and thereby shift the
10 spring along the brake shoe, said edge of the brake shoe being situated relatively to the threaded stem for varying the spring pressure of the shoe against the drum by such shifting.
- 15 3. A rebound check for spring vehicles comprising in combination with the two vehicle members between which the vehicle springs react, the means for varying the tension of the brake spring comprising a carrier by which said spring is held, the casing having an aperture in one of its side walls through which said carrier protrudes; a screw-threaded device mounted on the outside of the casing having thread engagement with the protruding end of said carrier, whereby the rotation of said threaded device
20 adjusts the carrier and thereby the spring with relation to the brake member for varying the point of action of said brake spring upon the brake member.
- 25 4. A rebound check for spring vehicles comprising in combination with the two vehicle members between which the vehicle springs react, the cylindrical member having a laterally situated and laterally open cylindrical cavity, the brake member comprising a pair of shoes positioned within said cavity and pivotally supported on the side wall of the casing adjacent said cavity for reaction outwardly against the inner surface of the
30 peripheral wall of said cavity, the brake spring being interposed between said two brake shoes for reacting outwardly against both of them; a carrier for said brake spring mounted in the casing wall on which the said

brake shoes are pivoted, and means for adjusting said carrier in alignment with the axis of the cylindrical member and the pivot of the brake shoes, whereby the distance of the points of bearing of the spring against the brake shoes from the brake shoe pivot is varied for varying the force of reaction of the spring against the brake shoes.

5. A rebound check for spring vehicles comprising a fixed hub, a rotatable brake drum, segmental brake shoes interposed between said hub and said drum, and a single compression spring member engaging each of said shoes to press the ends thereof outwardly into engagement with said drum.

6. A rebound check for spring vehicles comprising a fixed hub, a rotatable drum mounted to turn about said hub, means for connecting the drum to the vehicle axle, segmental brake shoes pivoted between said hub and drum, a single compression spring acting against the outer ends of said shoes to keep the same pressed into engagement with said drum, and means for adjusting said spring to vary the pressure thereof on said shoes.

7. A rebound check for spring vehicles comprising a fixed hub, a brake drum mounted to rotate about said hub, a pair of brake shoes pivotally mounted between said hub and drum, said pivotal mounting being fixed non-rotatably with respect to said hub, a compression spring member interposed between the outer ends of each shoe to keep the same pressed into engagement with said drum, a casing surrounding said drum and hub, and means extending exteriorly of said casing for adjusting said spring to vary the pressure thereof on said shoes.

In testimony whereof, I have hereunto set my hand at Chicago, Illinois, this 29th day of January, 1923.

CHARLES S. BURTON.
